(57) **CLAIM**

The ornamental design for a bottle, as shown and described.

DESCRIPTION

FIG. 1 is a front-top-left perspective view of a bottle showing my new design;

FIG. 2 is a rear-top-left perspective view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a right-side elevational view thereof; and,

FIG. 8 is a left-side elevational view thereof.

The dash-dot lines in the drawings depict boundaries of the claimed design that form no part thereof.

The dashed lines, the areas within them and the unshaded areas bounded by both broken lines and solid lines depict portions of the bottle that form no part of the claimed design.
